TAPE CARTRIDGE

Sheldon Lee Pastor, St. Paul, Minn., assignor to Minnesota Mining and Manufacturing Company, St. Paul, Minn., a corporation of Delaware

Filed Jan. 9, 1963, Ser. No. 73,113

Term of patent 14 years

(Cl. D26—14)

FIG. 1

FIG. 2

FIG. 4

FIG. 3

FIG. 5

FIG. 6

FIGURE 1 is a front, top and right side perspective view of a tape cartridge showing my new design;

FIGURE 2 is a front elevation of the cartridge of FIGURE 1;

FIGURE 3 is a bottom view;

FIGURE 4 is a left side elevation;

FIGURE 5 is a right side elevation; and

FIGURE 6 is a rear elevation thereof.

The dominant features of my new design are shown in full lines.

I claim:

The ornamental design for a tape cartridge, substantially as shown and described.
